Primary Examiner — Carla J Wright**CLAIM**

The ornamental design for a cell phone case, as shown and described.

DESCRIPTION

FIG. 1 is a front, right-side, and bottom perspective view of a cell phone case showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and

FIG. 7 is a bottom plan view thereof.

FIG. 8 is a rear, right-side, and bottom perspective view thereof; and,

FIG. 9 is an enlarged detail view of the encircled portion of FIG. 8.

The broken line circle in FIGS. 8 and 9 forms no part of the claimed design and delineates a portion of the cell phone case that is part of the claimed design and that is shown on an enlarged scale in FIG. 9.
